MOTEL FRONT

Warren W. Kane, Austin, Minn., assignor to Sterling Motels Co., Austin, Minn., a partnership

Application February 23, 1954, Serial No. 29,140

Term of patent 3½ years

(Cl. D13—1)

To all whom it may concern:

Be it known, that I, Warren W. Kane, a citizen of the United States of America, and a resident of Austin, county of Mower, State of Minnesota, have invented a new, original, and ornamental Design for a Motel Front, of which the following is a specification, reference being made to the accompanying drawing, forming a part thereof, wherein:

Figure 1 is a perspective view of a motel front showing my new design, said view being taken from a side and forward corner thereof, the dotted lines indicating a selective position of a harmonious wall in one type of installation;

Figure 2 is a side elevation of the same; and

Figure 3 is a perspective view taken from a position forwardly and from the opposite corner

of the motel front shown in Figure 1, the dotted lines indicating a selective harmonious wall positioned in another contemplated relation.

The dominant features of my design reside in the portions shown in full lines.

I claim:

The ornamental design for a motel front, as shown and described.
